O. A. PETERS

OIL FLOW TANK

Filed March 7, 1924

INVENTOR

Otto A. Peters.

UNITED STATES PATENT OFFICE.

OTTO A. PETERS, OF WICHITA FALLS, TEXAS.

OIL-FLOW TANK.

Application filed March 7, 1924. Serial No. 697,549.

To all whom it may concern:

Be it known that I, OTTO A. PETERS, a citizen of the United States, residing at Wichita Falls, in the county of Wichita and State of Texas, have invented new and useful Improvements in Oil-Flow Tanks, of which the following is a specification.

My invention relates to oil flow tanks, and it is my principal object to provide a device of this nature whereby the flow of oil into said tank may be inspected without releasing the gas pressure in said tank.

Further objects and advantages will be apparent as the invention is more fully disclosed.

With the foregoing in view, the invention resides in the novel subject matter hereinafter described, and claimed, the description being supplemented by the accompanying drawing forming a part of this application, wherein the various parts are referred to by numbers.

1 is a tank which may be of any convenient design. 2 is a covered manhole disposed on the top thereof. 3 is a cylindrical housing having the lower end thereof tapered in a cone shape, as shown at 3^a, and inserted into the top of the tank 1. 4 is a tubular member attached to the lower end of the housing 3 and extending downward in the tank 1 in an oblique position to prevent the oil from splashing to the bottom of the tank, thereby retarding agitation of the oil, the lower end of the tubular member 4 being spaced from the bottom of said tank below the oil level therein. 5 is a cover disposed on top of the housing 3 to enable inspection of the oil flowing therein. 6, 6^a and 6^b are pipes leading into the housing 3. 7 is a tubular member attached near the top of the tubular member 4, and extending downward longitudinally with the tubular member 4, the lower end of the tubular member 7 being submerged approximately six inches in the oil to enable the gas that accumulates in the tubular member 4 and the housing 3 to pass through the oil into the tank, and also to prevent the gas in the tank 1 from escaping through the tubular member 4 and the housing 3, when the inspection

cover 5 is opened. 8 is a valve disposed in the cover 5 for the purpose of releasing the gas pressure in the housing 3 before the cover 5 is opened. 9 is a tubular member attached to the top of the tank 1, for the purpose of conveying the gas therefrom to the place of consumption. 10 is a valve disposed near the bottom of the tank 1 for the purpose of draining the settling from the bottom of said tank. 11 is a valve attached to the tank 1 above the surface of the oil therein. 12 is a tubular member extending downward on the inside of said tank from the valve 11, the lower end of the tubular member 12 being submerged below the surface of the oil in said tank.

The device operates in the following manner: Oil coming into the housing 3 through the pipes 6 is lowered to the bottom of the tank 1 through the tubular member 4, the gas that accumulates in the tubular member 4 and the housing 3 passes into the tank 1 through the tubular member 7, it will be noted that the tubular member 4 is submerged deeper into the oil than the tubular member 7, thereby enabling the gas to follow the course of least resistance, which is through the tubular member 7, the gas pressure in the tank 1 forces the oil through the tubular member 12 and the valve 11 to the storage tank.

While it is believed from the foregoing description the nature and advantages of the invention will be readily apparent, I desire to indicate clearly that I do not limit myself to the specific construction herein shown and described, and that such changes may be resorted to, when desired, as fall within the scope of what is herein claimed.

What I claim is:

1. In an oil flow tank of the character described, the combination of a tank, a housing mounted on said tank, a plurality of tubular members attached to said housing exteriorly of said tank, a tubular member attached to the bottom of said housing and extending downwardly in said tank, and a second tubular member attached to the first mentioned tubular member near the upper end thereof to provide for release of gas pressure.

2. An oil flow tank as defined in claim 1, said housing having a cover with a valve disposed therein for the purpose set forth.
3. An oil flow tank as defined in claim 1, said second tubular member providing for release of gas in the first tubular member attached to the former tubular member near the top thereof and extending downwardly in said tank, the lower end thereof being

submerged below the surface of the oil in 10 the tank.

4. An oil flow tank as defined in claim 1, said tubular member attached to the bottom of the housing being disposed at an oblique angle downwardly with the lower 15 end thereof submerged below the surface of the oil in said tank.

OTTO A. PETERS.
